[57]CLAIM

The ornamental design for a compact disc storage wallet with attached handle, as shown and described.

DESCRIPTION

FIG. 1 is a perspective view of a compact disc storage wallet with attached handle showing my new design, the broken lines on the surfaces and edges of the cover being understood to represent stitching, and the broken lines showing legible indicia not forming any part of the claimed design; FIG. 2 is a front perspective view thereof shown in an open position; the broken line shown on the inner leaves in FIGS. 2 and 8 being shown to illustrate environmental subject matter and not part of the claimed design; FIG. 3 is a left elevation view of the invention illustrated in FIG. 2; FIG. 4 is a right elevation view of the invention illustrated in FIG. 2; FIG. 5 is a bottom plan view of the invention illustrated in FIG. 2; FIG. 6 is a top plan view of the invention illustrated in FIG. 2; FIG. 7 is a rear elevation view of the invention illustrated in FIG. 2; and, FIG. 8 is a front elevational view of FIG. 2;
